[57] **CLAIM**

The ornamental design for a garden lighting fixture, as
shown and described.

DESCRIPTION

FIG. 1 is a perspective view of a garden lighting fixture
showing my new design as seen from the front and left side
of the fixture;

FIG. 2 is a side view of the fixture, the other side being a
mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of an alternate embodiment
of a garden lighting fixture showing my new design as seen
from the front and left side of the fixture;

FIG. 8 is a side view of the alternate embodiment of the
fixture, the other side being a mirror image thereof;

FIG. 9 is a front elevational view of the alternate embodiment;

FIG. 10 is a rear elevational view of the alternate embodiment;

FIG. 11 is a top plan view of the alternate embodiment; and,

FIG. 12 is a bottom plan view of the alternate embodiment.
